APPARATUS FOR APPLYING CEMENT TO
RUBBERIZED FABRIC

Max Engler, Akron, Ohio, assignor to The General Tire & Rubber Company, Akron, Ohio, a corporation of Ohio

Application October 11, 1943, Serial No. 505,746

5 Claims. (Cl. 91—55)

This invention relates to apparatus for coating fabric with rubber cement and has for its object to provide a machine capable of applying a thin coating of cement rapidly and uniformly to the surface of the fabric.

A further object of the invention is to provide means for collecting and conducting away the inflammable volatile constituents of the cement that are vaporized from the cement applied to the fabric.

The invention also provides improved means for supporting and continuously moving the fabric past coating devices and through a drying chamber.

With the above and other objects in view, the invention may be said to comprise the apparatus as illustrated in the accompanying drawings hereafter described and particularly set forth in the appended claims with such variation and modification thereof as will be apparent to one skilled in the art to which the invention pertains.

Reference should be had to the accompanying drawings forming a part of the specification in which:

Figure 1 is a side elevation of apparatus embodying the invention;

Figure 2 is the longitudinal section through the cement chamber;

Figure 3 is a section taken on the line indicated at 3—3 in Figure 2;

Figure 4 is a section taken on the line indicated at 4—4 in Figure 2;

Figure 5 is a side elevation of the fabric unwinding and liner wind-up mechanism;

Figure 6 is a front elevation of the mechanism shown in Figure 5;

Figure 7 is a section taken on the line indicated at 7—7 in Figure 1;

Figure 8 is a side elevation of a modified form of apparatus embodying the invention, portions of the housing being broken away and shown in section, and

Figure 9 is a front elevation of the cement applying mechanism viewed as indicated at 9—9 in Figure 8.

In the accompanying drawings the invention is shown applied to apparatus for coating rubberized fabric with rubber cement in which the rubberized fabric is fed through cement applying and drying devices to apply a cement coating to the opposite sides thereof. As shown in Fig. 1, a fabric feed mechanism A is provided in the front end of the machine and the fabric passes from this feed mechanism through a coating

chamber B, a drying chamber C to a fabric wind-up mechanism D.

The fabric feed mechanism A is mounted on a frame 1, which is adapted to receive a fabric holding reel 2, that is detachably mounted in axially aligned bearings 3 and 4. At the top of the frame, above the reel 2, there is mounted a liner reel 5 that is detachably mounted at one end in a bearing 6 and detachably and nonrotatably secured at the opposite end to a shaft 7 journaled in the frame 1. As the fabric is delivered from the reel 2 the liner fabric is led from the reel 2 over a guide roller 8 and is wound on the reel 5. A take-off roller 9 bears yieldably upon the fabric on the reel 2, the roller 9 being guided for movement toward or away from the reel 2 in inclined slots 10 in the frame that are provided in opposite sides of the frame and disposed radially with respect to the reel 2. An electric motor 11, mounted on the frame 1, is connected by a sprocket chain 12 to a sprocket 13 rotatably mounted on the shaft 7, sprocket 13 being connected by a slip clutch 14 to the shaft 7 so that the liner wind-up reel 5 may be driven fast enough to keep the liner taut when reeling from a full fabric reel but is permitted to slip to prevent the exertion of excessive tension on the liner as the liner builds up on the reel 5. The clutch 13 may be adjusted to vary the pressure on the slip clutch by means of a hand wheel 15.

The motor 11 is connected by a sprocket chain 16 to a fabric feed roller 17 adjacent to base of the frame 1. The rubberized fabric is fed from the reel 2 over the take-off roller 9 and over a guide roller 18 to the driven feed roller 17. The fabric passes around the underside of the feed roller 17 and horizontally through an opening in the lower portion of the coating chamber B to a guide roller 19 positioned adjacent the rear end of chamber B. The fabric passes upwardly around the roller 19 and forwardly over an applicator roll 20 that engages the underside of the fabric. From the applicator roll 20 the fabric passes horizontally in a forward direction under and around a guide roller 21 in the front end of the chamber B, then upwardly and rearwardly over a second applicator roll 22, then rearwardly through the rear end wall of the chamber.

The direction of the travel of the shaft is reversed when passing over the rollers 19 and 20 and, since the fabric under tension engages these rollers through approximately 180° the rollers 19 and 21 are driven without slippage by the fabric. The first applicator roll 20 is driven through a sprocket chain 23 by the guide roller 18, and the

second applicator roll 22 is driven through a sprocket chain 24 by the guide roller 21. The ratio of the sprockets on the guide rollers and the applicator rolls is such that the applicator rolls are driven at a peripheral speed less than the linear speed of the fabric, preferably at a speed of about one-half the linear speed of the fabric.

Beneath the applicator rolls 20 and 22 cement reservoirs 25 and 26 are mounted, each reservoir being in the form of an open top receptacle, into which the lower portion of the applicator roll extends. The reservoirs 25 and 26 contain sufficient liquid cement to fill the same up to a point somewhat above the bottoms of the rolls 20 and 22 so that the reservoirs supply a film of cement to the rolls as the rolls are rotated.

By reason of the fact that the fabric is traveling faster than the periphery of each applicator roll, the cement is applied to the surfaces of the fabric in a uniform but extremely thin layer.

In view of the fact that the cement contains volatile inflammable constituents which are rapidly vaporized when exposed to the atmosphere in the form of a thin film on the fabric, means is preferably provided for continuously collecting and discharging the fumes given off by the fabric coatings. For this purpose a suction fan 27 is mounted above the coating chamber B and this fan is connected through a vertical suction conduit 28 with two horizontal branches 29 and 30, which extend laterally beneath the two horizontal runs of the fabric in the chamber B, the branches 29 and 30 being provided with upwardly flaring nozzles 31 and 32, which have their open ends closely adjacent the under side of the fabric, forwardly of the applicator roll 20 and rearwardly of the applicator roll 22 so that vapors given off by the films of cement on the fabric will be sucked through the nozzles 31 and 32 and be discharged through the suction conduit 28 and suction fan 27.

In order to properly condition the cement coatings on the fabric, it is desirable that the fabric be subjected to heat for a sufficient length of time to eliminate excess liquids from the cement. As shown in Fig. 1, the fabric passes rearwardly from the applicator roll 22 into the lower end of a tower drier C, which is provided with a horizontal row of guide rollers 33 adjacent the bottom thereof and a second row of guide rollers 34 adjacent the top thereof.

The fabric crosses under the rollers 33 and over the rollers 34 to provide a series of vertical runs within the drying chamber C.

The guide rollers 34 at the top of the chamber C are all driven at the same speed by sprocket chains 35, driven from a horizontal shaft 36 mounted in horizontal alignment with rollers 34 at the front of the chamber C. The shaft 36 is driven by a vertical shaft 37 which is driven by a motor 39 mounted on the housing B and driving a sprocket chain 38 that drives the shaft 37. Fumes are discharged from the interior of the chamber C through a stack 40 which may be provided with a damper 41 to regulate the draft.

Air is circulated through the drier chamber C by means of a fan 42 which is mounted alongside the chamber at the bottom thereof, the fan forcing air into the chamber C through a heater 43.

The chamber C may be provided with suitable doors 44 through which access may be had to the interior thereof.

In order to keep the fabric straight as many of the guide rollers as desirable may be in the form of spreader rollers as is common practice in the

art, such rollers being provided with oppositely disposed spiral ribs upon the periphery which exert a lateral tension on the fabric to hold it flat as it passes through the machine.

5 After passing through the chamber C the fabric passes over a guide roller 45 in alignment with the rollers 34 outside the chamber and under the guide roller 46 adjacent the bottom of the chamber. The fabric passes under the roller 46 to the 10 wind-up mechanism D which is mounted on a frame 47 and includes a fabric wind-up reel 48 that is driven by a sprocket chain 49 from an electric motor 50, the driving sprocket preferably being provided with a slip clutch such as provided 15 on the liner reel of the feed mechanism A. The wind-up reel maintains the desired amount of tension on the fabric and winds with the fabric a suitable liner which is fed from a supply reel 51 over a guide roller 52 to the reel 48. The wind-up reel 48 is detachably mounted like the reels 20 on the frame 1 so that the reels may be replaced when the wind-up reel is full and the liner reel is empty.

In Figures 8 and 9 of the drawings a modification is illustrated in which fabric from a feed mechanism not shown is fed through coating apparatus E and through a drier chamber F to a wind-up mechanism not shown, it being understood that feed and wind-up mechanisms such 30 as illustrated in connection with the modification first described may be used.

The coating apparatus E is mounted on a frame 60 which has a guide roller 61 at the bottom that guides the fabric received from the feed mechanism. The fabric passes under the guide roller 61 and over a guide roller 62 mounted on a frame above the roller 61, and then forwardly to a guide roller 63 and back over the roller 63 at an upward inclination over an applicator roll 40 64 to a front upper guide roller 65 and then rearwardly and upwardly over a second applicator roll 66. The applicator rolls 64 and 66 are provided with cement reservoirs 67 and 68, which supply a film of liquid cement to the surface of each of the rolls as it rotates in contact with the fabric. The rolls 64 and 66 are driven by sprocket chains 45 69 and 70 from the guide rollers 63 and 65 at a peripheral speed of about half the linear speed of the fabric.

50 To collect the more volatile of the liquid constituents of the cement, a suction fan 71 is mounted above the frame 60 and is connected by a vertical suction conduit 72 to horizontal suction inlets 73 and 74 located immediately beneath the fabric forwardly of the applicator roll 64 and rearwardly of the applicator roll 66.

The vapors given off by the cement when exposed to the air in a thin film on the fabric are discharged by the suction fan 71.

60 The fabric passes from the coating mechanism into the drying chamber F, which is in the form of an elongated horizontal chamber which is connected to a suction conduit 75 through a plurality of branches 76 leading from the conduit 65 75 to the top of the chamber F. The chamber is provided with air inlets 77 adjacent the bottom so that air is circulated through the drying chamber during the passing of the fabric therethrough.

The fabric passes from the front and to the 70 rear end of the chamber F under a guide roller 78 and over a guide roller 79 above steam coils 80, around a large guide roller 81 at the rear end of the chamber and forwardly beneath the steam coils 80 to a guide roller 82 adjacent the front 75 end of the chamber, and then rearwardly over

a guide roller 83 from which the fabric passes through an opening in the rear end of the chamber to the wind-up mechanism, additional steam coils 84 being provided beneath the lower horizontal run of fabric. During the passage of the fabric through the drying chamber F, the films of cement on the opposite faces of the fabric are subjected to the action of currents of air circulating upwardly through the chamber and heated by means of the steam coils 80 and 84. This heating of the fabric removes additional liquid constituents from the cement, leaving a uniform coating of cement upon the fabric that firmly adheres to the fabric and that is tacky, but solid enough to permit the necessary bending of the fabric without injury to the coating.

I claim:

1. Apparatus for coating fabric with rubber cement comprising means for supporting said fabric and continuously moving the same in superposed oppositely moving runs; including fabric driven guide rollers at the ends of said runs, applicator rolls engaging the under sides of oppositely moving runs of the fabric intermediate two of said rollers, and a driving connection between each applicator roll and one of the two guide rollers.

2. Apparatus for coating fabric with rubber cement comprising means for supporting said fabric and continuously moving the same in superposed oppositely moving runs; including guide rollers at the ends of said runs with each of which the fabric engages over an arc of more than ninety degrees, applicator rolls engaging the under sides of oppositely moving runs of the

fabric intermediate two of said guide rollers and having an arc of contact with the fabric that is less than 90°, and a driving connection between each applicator roll and one of said guide rollers for driving each applicator roll at a peripheral speed less than that of the guide roller to which it is connected.

3. Apparatus for coating fabric with rubber cement comprising means for supporting and advancing the fabric, applicator rolls for applying thin coatings of rubber cement to opposite sides of the fabric, suction means adjacent each applicator roll for collecting vapors given off by the thin layers of cement, and means for circulating heated air over the coated fabric.

4. Apparatus for coating fabric with rubber cement comprising means for moving the fabric, spaced guide rollers for supporting the fabric in superposed oppositely moving runs, applicator rolls engaging the underside of the fabric in each run, a suction nozzle closely underlying the fabric adjacent each applicator roll, and means for circulating heated air over the surface of the fabric.

5. Apparatus for coating fabric with rubber cement comprising means for moving the fabric, spaced guide rollers for supporting the fabric in superposed oppositely moving runs, applicator rolls engaging the underside of the fabric in each run, a suction nozzle closely underlying the fabric adjacent each applicator roll, a drying chamber, guide rollers for supporting the fabric in a plurality of runs in said chamber, means for circulating air through said chamber and means for heating the air.

MAX ENGLER.
